UNITED STATES PATENT OFFICE.

CHARLES W. COOPER, OF BROOKLYN, NEW YORK.

PROCESS OF AGITATING HIDES OR LEATHER SCRAPS.

SPECIFICATION forming part of Letters Patent No. 400,442, dated April 2, 1889.

Application filed July 6, 1888. Serial No. 279,198. (No model.)

To all whom it may concern:

Be it known that I, CHARLES W. COOPER, a citizen of the United States, residing in the city of Brooklyn, county of Kings, and State of New York, have invented an Improved Method of Treating Hides, Skins or Scraps, in Liquids, of which the following is a specification.

In the manufacture of leather from hides, or of glue from skins or scraps, it is frequently necessary to treat said hides, skins or scraps in a bath of water, or other liquid, either for the purpose of removing dirt or impurities therefrom, or for the purpose of chemically treating the said articles. In the washing operations referred to, or in the chemical treatment of the said hides, skins or scraps, it is generally desirable to constantly or occasionally agitate the water, or other liquid, in which they are contained, and stir the mass, so as to occasion the presentation of every part of the hide, and of every piece of the skins or scraps treated, to the action of the bath or to the chemicals therein contained or to the action of a gas forced into the said bath, and it is also desirable, in processes for the washing of, or the removal of impurities from, hides, skins or scraps, to cause every part of the surface of each of said articles to come into contact with other pieces of the mass in order that the impurities on their surfaces may be mechanically removed thereby. Heretofore in the washing and chemical operations incident to the treatment of hides, skins or scraps, various mechanical devices have been employed to agitate the mass but most of these devices have been open to the objection that they have involved the use of complicated heavy and expensive apparatus, and the use of costly machinery for the transmission of the necessary power.

The object of my invention is to provide a method by which hides, skins or scraps, in a bath of water or other liquid may, for the purposes above described, be thoroughly, conveniently and cheaply treated, and, generally stated, it consists in feeding air or suitable gas, into and at or near the bottom of, a vessel containing the material to be treated, whereby in the ascent of the air or gas through the body of the liquid, the hides, skins or scraps contained in said liquid are com-

pletely and thoroughly as to all their parts exposed to the action of said liquid or to the action of the gas so fed into the tank, and are also rubbed one against the other,—all of which results are highly advantageous in preparing the articles specified for the uses to which they are ultimately applied.

Apparatus by the use of which my method may be practiced is shown in the accompanying drawings, in which—

Figure 1 is an elevation partly in section of an apparatus by which my method may be practiced with convenience and efficiency. Fig. 2 is a fragmentary perspective view of a modified form of apparatus. Fig. 3 is a fragmentary perspective view of a modified form of an apparatus. Fig. 4 is a central sectional elevation of still another modified form of apparatus. Fig. 5 is a detail view of a system of air or gas pipes suitable for employment in connection with the apparatus shown in the drawings.

Similar letters of reference indicate corresponding parts.

In the apparatus shown in Fig. 1, A is a containing-vessel or the inner vessel of the apparatus, (shown as a cylindrical tank,) provided with a slatted or perforated bottom, B, and with liquid-escape openings a at or near its top. The liquid-escape openings, as well as the openings in the slatted bottom, are of such size as to prevent the escape of the hides, skins, or scraps treated, and to only permit of the escape of the liquid in which they are contained. A^x is a second tank, termed herein the "inclosing-tank," which as to its sides and bottom surrounds and incloses the inner tank. The relative size of each of the two tanks is such that an annular space, C, of a given area is formed between the two walls, and a space, D, between the bottoms, of the tanks. The tank A is supported within the tank A^x in any preferred manner, conveniently by being superimposed upon trusses or supporting-bars E, extending across the interior of the tank A^x near the bottom thereof. Q is a pipe leading from any desired source of liquid-supply and discharging into the tank A. X is a cock by which the liquid contents of the tanks may be drawn off. F is an air or gas pipe entering the tank A^x at or near the bottom thereof, extending nearly across the same, and pro-

vided with a system of transverse or other branch pipes, f , which lie beneath and within a space coextensive and coincident with the perforated bottom of the tank A, and are provided with a number of escape-orifices, f' . G is an air or gas force-pump, from which the pipe F leads.

The operation of the apparatus in the practice of my method will be readily understood.

- 10 The tank A is about half filled with the hides, skins or scraps to be treated, and the tank A^x is filled to the proper level with water or other liquid. The pump G being put into operation, air or gas as the case may be is forced through the pipe F and its branches f , escapes at the outlet-orifices f' , and rises through the slatted bottom B of the tank A, and causes the ebullition of the contents of the tank A and the thorough and intimate contact of the liquid and the hides or skins. By means of the liquid inlets and outlets the water contained in the tanks A and A^x is permitted to freely circulate from one to the other. Thus the process is facilitated.

- 15 25 It is obvious that many constructions of apparatus characterized by diversity of form but by unity of principle, might be devised to carry out my method. Thus, for instance, in Fig. 2, I have shown the inner tank A as rectangular and so constructed within the tank A^x that the side and end of the latter serve as the side and end of the former, the liquid-escape outlets a being formed in but one side of the vessel A. They may however, if desired, be formed in the end of said vessel.

30 35 Fig. 3 of the drawings illustrate a square exterior tank A^x , within which the interior tank A is shown as mounted upon pedestals a^x , and as provided with the usual slatted bottom B, and also with a slatted roof or lid I, in lieu of the escape outlets a of Fig. 1.

40 45 In Fig. 4 of the drawings is shown a form of apparatus embodying a conical exterior tank, and a conical interior tank the upper end of which fits within and is secured to the upper end of the outer tank. The bottom and sides of the inner tank are slatted so that the liquid-escape outlets extend from its top to its bottom.

50 55 In the apparatus shown in Fig. 4 the hides or skins to be treated, and liquid, having been

placed therein, the gas or air being forced into the bottom of the tank through the perforated pipes, which, it is to be remembered, cover only an area coextensive with the slatted bottom of said tank, rises vertically within that portion of the tank included between the dotted lines a b and c d , shown in said figure, and causes the ascent of the mass undergoing treatment, the air or gas is freed on reaching the surface of the tank, whereupon the liquid flows toward that part of the tank exterior to the part contained between said dotted lines, returns to the bottom of the tank, and re-enters the slatted tank at a point below the material undergoing treatment.

55 60 It is to be understood that while in the claims I refer to the introduction of air to the mass contained in a tank to elevate it,—the word is not to be understood in a literal sense but is to be taken as signifying not only air, but gases of any character.

65 Having thus described my invention, I claim:

1. The method of agitating or treating hides in liquid, which consists in subjecting said hides in a receptacle, (through orifices in the sides or bottom of which the said liquid may flow into and out from a common liquid reservoir), to the action of currents of air introduced within and at or near the bottom of said receptacle, as specified.

70 75 80 85 90 95 2. The method of treating hides, or glue scraps, in water or other liquid, in the chemical treatment thereof, or for the removal of impurities therefrom, which consists in feeding air, or a suitable gas, into, and at or near the bottom of, a vessel containing the mass to be treated, in such manner as to cause the hides or scraps treated to be agitated in contact with each other, and, at the same time, to cause the water or liquid in said vessel to flow or circulate from the upper part of said vessel to the lower part thereof and under the hides or scraps therein, as specified.

95 In testimony that I claim the foregoing as my invention I have hereunto signed my name this 30th day of June, A. D. 1888.

CHAS. W. COOPER.

In presence of—

W. H. WOODHULL,
AUGUST HEINE.
